UNITED STATES PATENT OFFICE.

MARY V. KAVANAGH, OF NEW YORK, N. Y., ASSIGNOR TO THE BUTTERICK PUBLISHING COMPANY, (LIMITED,) OF SAME PLACE.

DESIGN FOR A LITTLE GIRL'S COAT.

SPECIFICATION forming part of Design No. 17,943, dated December 13, 1887.

Application filed November 15, 1887. Serial No. 235,266. Term of patent 3½ years.

To all whom it may concern:

Be it known that I, MARY V. KAVANAGH, of the city, county, and State of New York, have invented and produced a new and original Design for a Pattern of a Little Girl's Coat; and I do hereby declare that the engraved prints accompanying this specification convey to any one accustomed to using paper patterns a clear understanding of how a garment made up by the pattern will appear.

The design shows a round waist that laps in double-breasted style, side-skirt sections depending from the waist and exhibiting gathers

across the hips, a back-skirt section that reaches to the neck and falls over in hood style, coat-sleeves with puffs reaching below the elbows, and a shawl-collar.

What I claim as my invention, and desire to secure by Letters Patent, is—

The design for a little girl's coat, as shown in the engraved prints accompanying this specification.

MARY V. KAVANAGH.
